HORACE H. BURDETT, OF HOPEDALE, MASSACHUSETTS, ASSIGNOR TO DRAPER CORPORATION, OF HOPEDALE, MASSACHUSETTS, A CORPORATION OF MAINE

LOOM STOPPING AND LET-BACK MECHANISM

Application filed October 7, 1929. Serial No. 397,765.

This invention relates to improvements in take-up mechanisms for looms and particularly to the means for releasing the clutch to permit let-back of the take-up roll upon detection by the filling fork of failure of filling.

In usual constructions the clutch of the take-up mechanism is released upon detection by the filling fork of failure of filling through the movement of the filling fork slide which actuates a bell crank lever pivotally mounted upon a controller rod to transmit motion through a link to the clutch-releasing lever. In order to insure proper disengagement of the clutch, careful adjustments of the weft hammer and of the mechanisms for transmitting the force therefrom to the clutch-shifting lever is required. Sometimes in the operation of the loom the clutch fails to disengage and in endeavouring to overcome this difficulty improper adjustments are made which result in causing the feeler slide to engage its stop before the actuating cam for the weft hammer has reached its maximum position, thereby imposing a strain upon the arm of the weft hammer which engages the cam. This is likely to result in injury or breakage of some part of the weft hammer or of the slide. In other instances the adjustment is such as to permit too great a forward movement of the slide and this results in opening the clutch too far and imposing such force upon the mechanism which transmits motion from the slide to the clutch-actuating element as to vary the adjustments thereof or bend or break certain of the parts of the motion-transmitting mechanism.

One of the objects of the present invention is to provide yieldable means intermediate of the weft hammer actuating cam and the weft hammer which will avoid breakage or injury to the weft hammer or the slide.

A further object of the invention is to provide mechanism through which the filling fork slide actuates the clutch-releasing lever with yieldable means which will prevent undue strain upon such power transmitting mechanism.

A further and very important object of the invention is to provide means for actuating the clutch directly from the weft hammer,

thus avoiding the imposition of any unusual strain upon the mechanisms which are operated through the movement of the filling fork slide, and means for adjusting such mechanisms to insure proper operation of the clutch-releasing means.

These and other objects and features of the invention will more fully appear from the following description and the accompanying drawings and will be particularly pointed out in the claims.

The present invention relates to improvements in take-up mechanisms of the general type illustrated in the patent to Rhoades No. 913,915 granted March 2, 1909, and the prior patent to Emery No. 648,903 granted May 1, 1900, referred to therein.

Inasmuch as this general type of mechanism is well known in loom constructions, only a sufficient portion of the loom is shown in the drawings to illustrate the embodiment of the present invention therein.

In the drawings:

Fig. 1 is a vertical sectional view of a portion of the loom looking toward the loom side and illustrating the present invention as applied to the take-up mechanism of a loom, and illustrating such portions of the usual loom structure as are necessarily associated therewith;

Fig. 2 is a detail sectional view on line 2—2 Fig. 1, illustrating means for permitting the cam-engaging arm of the weft hammer to yield to unusual force;

Fig. 3 is a front elevation of the mechanism illustrated in Fig. 1;

Fig. 4 is an enlarged detail view in longitudinal section, on line 4—4 Fig. 1, of the link mechanism for controlling and actuating the clutch-shifting lever;

Fig. 5 is an enlarged detail view of a portion of the bell crank lever which is rotatably mounted upon the controller rod and transmits motion from the feeler slide to the means for positioning the link through which the clutch-shifting lever is actuated; and,

Fig. 6 is a side view of the portion of the bell crank lever illustrated in Fig. 5.

The usual loom mechanism, which is illustrated in the accompanying drawings, com-

prises the loom side 1, the take-up stand 2, which is mounted upon the usual cross girder, the controller rock shaft 3, the breast beam 4, which is mounted upon the loom side, the weft hammer 5, which is pivotally mounted upon a shaft or stud 6, and is actuated through an arm 7 having adjustably secured to its opposite end a shoe 8 which engages a cam 9 upon the cam shaft 10. The usual filling fork slide 11 is slidably mounted in a suitable stand secured to the breast beam and the filling fork 12 which is pivotally secured to the rear end of the slide is provided with a loop 13 adapted to be engaged by a hook 14 upon the weft hammer and actuated by the vibratory movement of the weft fork when the filling fork is not swung about its pivot by engagement of the tines thereof with the filling thread, or in other words upon detection of failure of filling.

The take-up mechanism (not shown) may be of a usual character driven through a train of gears (not shown), but which comprises a gear 15 which engages a gear 16 rotatably mounted upon the shaft 17 which is journaled in the bearing of a suitable bracket 18 mounted upon the loom side. The gear 16 is provided with a clutch face 19 which engages a complementary clutch face 20 upon a sliding clutch member 21 which is feathered upon the shaft 17. The slideable clutch member 21 is actuated by a clutch-shifting lever 22 actuated by suitable mechanism controlled by the movement of the filling fork slide.

The mechanisms above described may be and desirably are of usual construction and usual means may also be provided to limit the let-back of the take-up roll upon detection of failure of filling by the filling fork.

In usual constructions the forward reciprocation of the filling fork slide, caused by the engagement of the loop of the filling fork with the weft hammer upon detection of failure of filling, actuates a bell crank lever which is pivotally mounted upon the controller shaft 3 to force downwardly a link which is directly connected to the clutch-shifting lever 22.

Under certain circumstances above described, such as improper adjustment of the parts, the movement of the weft hammer is unduly limited, or undue resistance is imposed upon the weft hammer which is likely to result in breakage of certain parts of the power transmitting mechanism. In order to overcome this difficulty the present invention contemplates the provision of resilient means intermediate of the weft hammer and the cam by which it is actuated which will yield sufficiently to avoid such injury or breakage. This is accomplished in the construction illustrated in the drawings by forming the weft hammer arm in two sections, one of which is integral with the fulcrumed portion 65 of the weft hammer and extends downwardly

and rearwardly therefrom, and is provided with a widened end portion 23 having laterally extending flanges 24 and 25 which embrace an arm 26 which is pivotally connected by a stud 27 to said integral portion and extends therefrom over the actuating cam 9 and to which arm the shoe 8 is adjustably attached. A spring, or preferably a plurality of springs 28 are interposed between the arm 26 and the flange 25 of the end portion of the integral arm of the weft hammer.

By reason of this construction the arm 26 is permitted to yield if the weft hammer or the slide engages an obstruction which prevents further movement thereof before the high portion of the cam engages the shoe 8, or if too much resistance is imposed upon the weft hammer by reason of too great movement of the movable clutch member, or by reason of improper adjustment of the power transmitting parts. Injury and breakage of the weft hammer arm or of the power transmitting mechanisms is thereby avoided. It will be obvious that this or equivalent means may be imposed between the weft hammer and its actuating cam in usual types of construction as well as in the constructions embodying other features of the invention illustrated herein.

The present invention also contemplates the provision of novel mechanism for releasing the clutch, more particularly comprising means for actuating the clutch-shifting lever directly from the weft hammer, or some other continuously vibrating member. In the construction illustrated herein the weft hammer is provided with a forward extension which, as shown, comprises an arm 29 having an enlarged flanged end which is secured to a boss 30 upon the weft hammer and at its forward end with an offset extension 31 adapted to engage a shoulder 32 upon a link 33 which has an offset lower end 34 pivotally connected to the clutch-shifting lever 22.

The offset extension 31 desirably is L-shaped and adjustably connected by bolt and slot connections to the end of the arm 29, the contacting faces of the members desirably being serrated to provide a rigid interlocking engagement.

The link 33 has a pin 35 at its upper end which engages slots 36 in the bifurcated lower end 37 of the lower section 38 of an extensible positioning member, the upper end of which is engaged and actuated by a bell-crank lever which is mounted upon the controller rod and which is provided with an arm extending into the path of the filling fork slide. The upper section 39 of the sectional positioning member is adjustably secured to the lower section by a bolt and slot connection 40 and 41. A transverse slot or recess 42 is provided in the upper section 39 of the positioning member adjacent its end to receive a pin or cylindrical arm 43 of the bell crank lever which is actuated by the

movement of the filling fork slide. A spiral spring 44, seated at its lower end upon the bottom of the recess and at its upper end engaging the pin 43, permits a yielding movement between the pin and positioning member if too great resistance would be otherwise imposed upon the pin. An adjusting screw 45, threaded into the upper end of the positioning member and extending into engagement with the pin 43, provides means for accurately adjusting the relative positions of the upper end of the member and the bell crank lever.

The upper end of the section 39 of the positioning member is provided with a lateral extension 46 which is pivotally connected by a pin 47 to the ear 48 of a bracket 49 which is secured to the breast beam. By reason of this construction the downward movement of the positioning member, caused by the bell crank lever, swings the lower end of the member laterally about the pivot 47, thereby moving the upper end of the link 33 from normal position, illustrated in dotted lines in Fig. 3, into full line position shown in said figure, and positioning the shoulder 32 of the link 33 in the path of the offset end 31 of the weft hammer extension 29, so that continued movement of the weft hammer will force the link 33 downwardly and consequently actuate the clutch-shifting lever 22 to release the clutch.

In the present construction the bell crank lever, which actuates the sectional positioning member, is of improved construction adapted to permit accurate adjustment. It is formed in two parts, one of which comprises a bearing or boss 50 which is rotatably mounted upon the controller rod 3 and is provided with an upwardly extending arm 51 having a slot 52 therein, the other arm of the bell crank being the pin 43 which enters the slot in the upper section 39 of the positioning member as above described. The other member of the bell crank comprises an arm 53 which is mounted upon the controller shaft 3 and extends upwardly in engagement with the arm 51 of the bell crank member and has at its upper end a lateral extension or pin 54 which lies in the path of the forward end of the filling fork slide.

The arm 53 is secured to the arm 51 of the bell crank member by a bolt 55 or machine screw which extends through the slot 52 and is adapted to permit suitable adjustments between the arm 53 and the arm 51 of the bell crank member. By reason of this adjustment and also by the adjustment of the screw 45 in the end of the positioning member, a very accurate positioning of the parts of the mechanism for controlling the link member 33 is provided.

In the operation of the machine, therefore, when failure of filling is detected by the

filling fork, the loop of the filling fork is engaged by the weft hammer and the filling fork slide moved forwardly, thereby engaging and actuating the arm 53 of the bell crank lever which is mounted upon the controller shaft 3. The rocking movement of the bell crank causes the pin 43 to force the sectional positioning member downwardly, thereby swinging its lower end laterally and moving the upper end of the link 33 laterally until its shoulder 32 is positioned in the path of the offset end portion 31 of the weft hammer extension 29.

By reason of this construction very little force is required to be transmitted by the movement of the filling fork slide to position the shoulder of the link 33 in the path of the weft hammer extension. Consequently, no sufficient force is imposed upon the adjusting mechanisms to interfere with the proper maintenance of their adjustments.

Continued movement of the weft hammer after the shoulder of the link 33 has been placed in the path of the weft hammer extension causes the link 33 to be positively depressed by the movement of the weft hammer to actuate the clutch-shifting mechanism. Consequently, proper release of the clutch members will be insured, notwithstanding the force required to disengage the teeth of the clutch produced by the tension of the goods when such heavy materials, as canvas or duck are being woven.

By reason of the present invention, therefore, interference with the free action of the filling fork slide is substantially avoided, as well as the application of great resistance to the arm of the weft hammer which engages the filling fork. Positive means are provided for actuating the clutch-shifting lever directly from the weft hammer, or some other continuously vibrating member of the loom which may be employed in place thereof.

By reason of the yielding connection between the bell crank lever, which is pivotally mounted upon the controller rod and the positioning member which is operated by it, the danger of varying adjustments or injuring moving parts is avoided, and by the multiplicity of adjustments proper coordination of the movements of the various parts may be accurately made and maintained so that the objectionable features of the clutch-actuating mechanism heretofore described may be readily and entirely overcome.

Having thus described the invention, what is claimed as new, and desired to be secured by Letters Patent, is:

1. Mechanism for actuating the clutch-shifting means of the let-back mechanism of a loom comprising a positively and continuously actuated vibratory member and means acting upon detection, by the filling fork, of failure of filling to effect a direct

connection between said vibrating member and said clutch-shifting means operable to disengage the members of the clutch.

2. Mechanism for actuating the clutch-shifting means of the let-back mechanism of a loom comprising an extension of the weft hammer and means actuated by the movement of the filling fork slide upon detection of failure of filling to effect a direct connection between said weft hammer extension and said clutch-shifting means operable to disengage the members of the clutch.

3. Mechanism for actuating the clutch-shifting means of the let-back mechanism of a loom comprising an extension of the weft hammer and means actuated by the movement of the filling fork slide upon detection of failure of filling to effect a direct connection between said weft hammer extension and said clutch-shifting means operable to disengage the members of the clutch, and yieldable means intermediate of the filling fork slide and the connecting means actuated thereby operable to prevent injury to the clutch-operating mechanism upon excessive movement of the filling fork slide or by excessive gripping of the clutch.

4. Mechanism for actuating the clutch-shifting means of the let-back mechanism of a loom comprising an extension of the weft hammer and means actuated by the movement of the filling fork slide upon detection of failure of filling to effect a direct connection between said weft hammer extension and said clutch-shifting means operable to disengage the members of the clutch, and yieldable means intermediate of the weft hammer and its actuating cam acting to prevent injury to the weft hammer or the mechanisms actuated thereby.

5. In a loom comprising a weft hammer, an actuating cam therefor, a filling fork slide having a filling fork to engage said weft hammer upon detection of failure of filling, and let-back mechanism having a clutch-shifting lever, clutch-releasing mechanism comprising a forward extension of said weft hammer, a link pivotally connected at its lower end to said clutch-shifting lever having a lateral shoulder to engage said weft hammer extension, but normally lying out of the path thereof, means connected to the upper end of said link operable by said filling fork slide upon actuation by said weft hammer to move the upper end of the link laterally and thereby to position said shoulder in the path of said weft hammer extension, whereby continued movement of said weft hammer will positively actuate said clutch-shifting lever to disengage the clutch.

6. In a loom comprising a weft hammer, an actuating cam therefor, a filling fork slide having a filling fork to engage said weft hammer upon detection of failure of filling, and let-back mechanism having a clutch and a

clutch-shifting lever, clutch-releasing mechanism comprising a forward extension of said weft hammer, a link pivotally connected at its lower end to said clutch-shifting lever having a lateral shoulder to engage said weft hammer extension, but normally lying out of the path thereof, a positioning member pivotally connected to the upper end of said link, yieldable means intermediate of the upper end of said positioning member and said filling fork slide operable upon actuation of said slide by said weft hammer to swing the upper end of the link laterally and thereby position its shoulder in the path of said weft hammer extension, whereby continued movement of the weft hammer will positively actuate the clutch-releasing lever to disengage said clutch.

7. In a loom comprising a weft hammer, an actuating cam therefor, a filling fork slide having a filling fork to engage said weft hammer upon detection of failure of filling, and let-back mechanism having a clutch and a clutch-shifting lever, clutch-releasing mechanism comprising a forward extension of said weft hammer, a link pivotally connected at its lower end to said clutch-shifting lever having a lateral shoulder to engage said weft hammer extension, but normally lying out of the path thereof, a positioning member pivotally connected to said link and having at its upper end a lateral extension, means pivotally connecting said extension to a stationary part of the loom, a bell crank lever pivotally mounted upon said controller rod having an arm extending into the path of the filling fork slide, and an arm engaging the upper end of said positioning member operable by said filling fork slide upon actuation by said weft hammer to cause said positioning member to swing the upper end of said link laterally, and thereby position its shoulder in the path of the weft hammer extension, whereby continued movement of said weft hammer will positively actuate said clutch-shifting lever to disengage the clutch.

8. In a loom comprising a weft hammer, an actuating cam therefor, a filling fork slide having a filling fork to engage said weft hammer upon detection of failure of filling, and let-back mechanism having a clutch and a clutch-shifting lever, clutch-releasing mechanism comprising a forward extension of said weft hammer, a link pivotally connected at its lower end to said clutch-shifting lever having a lateral shoulder to engage said weft hammer extension, but normally lying out of the path thereof, a positioning member pivotally connected at its lower end to said link and having a recessed upper end provided with a lateral extension, means pivotally connecting said lateral extension to a stationary part of the loom, a bell crank lever pivotally mounted upon said controller

rod having an arm extending in the path of the filling fork slide, and an arm extending into the recess in the upper end of said lever, a spring in said recess beneath said arm, and
 5 an adjusting screw in the end of said lever engaging said arm providing an adjustable and yielding connection between said lever and said positioning member acting to prevent injury to the mechanism upon excessive movement of said filling fork slide, and operable upon actuating of said filling fork slide by said weft hammer to swing the upper end of said positioning member laterally and thereby position said shoulder
 10 in the path of the weft hammer extension, whereby continued movement of said weft hammer will positively actuate said clutch-shifting lever to disengage the clutch.

9. In a loom comprising a weft hammer, an actuating cam therefor, a filling fork slide having a filling fork to engage said weft hammer upon detection of failure of filling, and let-back mechanism having a clutch and a clutch-shifting lever, clutch-releasing mechanism comprising a forward extension of said weft hammer, a link pivotally connected at its lower end to said clutch-shifting lever having a lateral shoulder to engage said weft hammer extension, but normally lying out of the path thereof, a positioning member pivotally connected at its lower end to the upper end of said link and having at its upper end a lateral extension pivotally connected to a stationary part of the loom, a bell crank lever comprising a sleeve rotatably mounted upon said controller rod having an arm adjustably secured to a co-operating arm also mounted upon said controller rod and extending into the path of the filling fork slide and a forwardly extending pin engaging the upper end of said link operable upon actuation of said bell crank lever by the filling fork slide to swing the upper end of said link laterally and thereby to position said shoulder in the path of the weft hammer extension, whereby continued movement of said weft hammer will positively actuate said clutch-shifting lever to disengage the clutch.

50. 10. A loom comprising a weft hammer actuating cam, a weft hammer having a rearwardly extending arm formed in relatively yieldable sections engaging said cam and a forward extension, a filling fork slide having a filling fork to engage said weft hammer upon detection of failure of filling, let-back mechanism having a clutch-shifting lever, means for actuating said clutch-shifting lever including a link pivotally connected at its lower end to said clutch-shifting lever and provided with a shoulder to engage the weft hammer extension, but normally lying out of the path thereof, and means operable by said filling fork slide when actuated by said weft hammer to move the upper end of said

link laterally and thereby position said shoulder in the path of the weft hammer extension.

In testimony whereof, I have signed my name to this specification.

HORACE H. BURDETT.
